By Richard Evert,

ATTORNEY

UNITED STATES PATENT OFFICE.

EVERT McDONALD, OF MONON, INDIANA.

SEWING OUTFIT.

1,293,492.

Specification of Letters Patent.

Patented Feb. 4, 1919.

Application filed December 11, 1917. Serial No. 206,698.

To all whom it may concern:

Be it known that I, EVERETT McDONALD, a citizen of the United States, residing at Monon, in the county of White and State of Indiana, have invented certain new and useful Improvements in Sewing Outfits, of which the following is a specification.

This invention relates to a sewing rack and has for its object the production of a simple and efficient sewing rack for conveniently supporting the different articles which are used while sewing.

Another object of this invention is the production of a simple and efficient rack, wherein the different articles used in sewing are conveniently arranged upon a supporting board.

With these and other objects in view this invention consists of certain novel constructions, combinations and arrangements of parts as will be hereinafter fully described and claimed.

In the drawings:—

Figure 1 is a front elevation of the rack, Fig. 2 is a section taken on line 2—2 of Fig. 1,

Fig. 3 is a section taken on line 3—3 of Fig. 1,

Fig. 4 is a section taken on line 4—4 of Fig. 1,

Fig. 5 is a detail perspective view of one of the scissor supporting brackets.

By referring to the drawings, it will be seen that 1 designates the supporting board which is provided with suitable apertures 2 for permitting a securing means to pass therethrough.

A pin cushion 3 is carried upon the supporting board or plate 1 and a tray 4 is carried upon the supporting board 1 to one side of the cushion 3 and is carried or supported upon the supporting brackets 5. This tray 4 is provided with a central partition 6 for dividing the tray 4 into a button containing compartment 7 and a dress hook containing compartment 8. A shelf 9 is supported below the tray 4 by means of a bracket 10 and this shelf 9 is adapted to constitute an efficient support for a thimble or other article 50 used in sewing, when the same is not in use.

A darning needle supporting rack 11 is carried upon the supporting board or plate 1 and is engaged and supported by a bracket 12. This darning needle supporting rack 11 55 is provided with a plurality of apertures 13

through which apertures are adapted to pass, darning needles and the like. A cushion 14 is supported directly below the darning needle support 11 and is adapted to constitute a support or rest for the lower ends of the darning needles which are adapted to extend through the supporting rack 11.

A pair of scissor supporting brackets 15 are secured to the supporting board or plate 1. These racks are substantially U-shaped in cross section and are struck from a single sheet of metal having a laterally extending tongue 16 struck therefrom which tongue 16 is adapted to extend into the supporting board or plate 1 as shown clearly in Fig. 2 of the drawing. The scissors are adapted to be placed within the scissor supporting bracket 15, by having the respective ends fitting or resting within the respective brackets 15.

A knife supporting lug 16' is secured to the plate or board 1 and is preferably triangular shape in cross section, tapering toward the top edge thereof. The lug 16' is provided with a notch 17 upon the upper face thereof within which is seated a cutting knife or blade 18, the lug 16' being dished out upon the top thereof adjacent the notch 17 as indicated by the numeral 19. 85

A spool supporting rod 20 has one end seated in a post 21 and the other end passes through an apertured post 22. The rod 20 is adapted to be moved through the post 22 to such a position as to allow the rod 20 to be disengaged from the post 21. In this manner suitable spools containing thread may be placed over the rod 20. A clamping screw 23 extends through the post 22 and engages the rod 20 for firmly holding the rod in a set position.

From the foregoing description it will be seen that a very simple and efficient device has been produced which will be very convenient for a seamstress wherein all of the necessary articles used in sewing may be conveniently supported in order to permit the seamstress to have ready access thereto.

What is claimed is:—

A sewing rack comprising a support, various article supporting means carried thereby, a plurality of scissor supporting brackets carried by said support and arranged in spaced relation, each bracket being substantially U-shaped in cross section and pro- 110

vided with an inwardly extending tongue, said bracket provided with an upwardly extending ear near each end upon the opposite sides of said tongue and adapted to normally lie flat against the support, for reducing any upward twisting movement of said scissor supporting bracket when said bracket is forced flat against said support, and said tongue adapted to extend into said support

for holding said bracket in engagement therewith.

In testimony whereof I affix my signature in presence of two witnesses.

EVERT McDONALD.
